UNITED STATES PATENT OFFICE.

HERMAN G. GROSSE, OF CHICAGO, ILLINOIS.

IRONING-BOARD.

1,291,484.

Specification of Letters Patent.

Patented Jan. 14, 1919.

Application filed May 18, 1916. Serial No. 98,244.

To all whom it may concern:

Be it known that I, HERMAN G. GROSSE, a citizen of the United States, and a resident of Chicago, in the county of Cook and State of Illinois, have invented certain new and useful Improvements in Ironing-Boards; and I do hereby declare that the following is a full, clear, and exact description thereof, reference being had to the accompanying drawings, and to the characters of reference marked thereon, which form a part of this specification.

This invention relates to improvements in ironing boards and refers more specifically to that type of ironing board designed more specifically for ironing skirts, shirtwaists and like articles of apparel.

Among the objects of the invention is to provide an improved construction of ironing board embracing, in combination with an ordinary skirt board, a sleeve board over which the sleeves of a waist or like garment are stretched to iron the same, so constructed and arranged as to permit the sleeve board to be swung bodily toward and away from the main ironing board so as to permit the full length of the ironing board to be utilized when the sleeve board is thus swung away therefrom and also arranged to enable the sleeve of a garment to be ironed, when supported on the sleeve board, in the same position and by the same hand which the operator employs in ironing a skirt or other garment on the main ironing board.

Other objects of the invention are to improve and simplify ironing boards, and the invention consists in the combination and arrangement of the parts hereinafter described and shown in the drawings, and is pointed out in the appended claims.

In said drawings:

Figure 1 is a plan view of an ironing board embodying my invention.

Fig. 2 is a side elevation thereof.

The main board 10, over which such tubular articles as skirts are placed to iron the same, is made widest at its heel end and tapers toward its other end, in the usual manner, and said board is supported at its wider or heel end upon the horizontal frame or bracket 11 of a stand 12. Said stand is formed with a base 13 that may be bolted to the floor, or it may be made sufficiently massive to support the board without permanent attachment to the floor. Said board is preferably supported on the bracket 11 by en-

gaging at its heel end under a hook-shaped flange 14 rigid with the bracket and the board is provided between its ends with a downwardly opening socket that is engaged by an upstanding stud 14^a which rises from the bracket 11. Between said flange 14 and said stud the board rests on narrow horizontal ribs 14^b. This construction permits the main board to be readily removed from the frame by merely raising the front end of the board to disengage it from the stud 14^a and by thereafter withdrawing the board from the flange 14.

15 designates a sleeve board which, as herein shown, is arranged above the plane of the main board, but, as will hereinafter appear, it may be equally well arranged below the main or skirt board. The said sleeve board is made widest at its front end and tapers toward its rear end, or toward the wider end of the main or skirt board. It is supported at its wider front end upon the forward or free end of a swinging L-shaped arm 16, the lateral terminal portion 17 of which is hinged on an upright shaft 18 that is supported in any suitable manner in rearwardly extending brackets 19, 19, of the main supporting frame 11. The laterally directed end 17 of said arm 16 is made of a length to extend somewhat beyond one side of said main or skirt board 10. Said sleeve board 15 is fixed to a frame or plate 20 that is hinged, as by means of a stud 21, indicated in dotted lines in Fig. 2, in an upstanding bearing 22 at the free end of the arm 16. When the sleeve board is not required to be used, it may be swung away from the main or skirt ironing board 10 to or beyond the position illustrated in Fig. 1, so as to permit the board 10 to be partially or wholly employed to support an article of apparel to be ironed thereon, and without requiring substantial space beyond the side of the main board to receive the outwardly swung or adjusted sleeve board. The dotted line position of the sleeve board 15 indicates its position for use, and this position, by reason of the hinge connection of the arm 16 with the shaft 18, and the hinge connection of the sleeve board frame 20 with the arm 16, permits said sleeve board to be adjusted near that side of the ironing board on which it is convenient for the operator to stand when ironing garments supported on both the main ironing board and the sleeve board, and also permits the sleeve

board to be adjusted generally parallel to the longitudinal axis of the main or skirt board.

The said sleeve board supporting arm 5 just clears the main or skirt board, and 15 preferably the free end of said arm may be provided with a widened bearing or foot 23 to bear upon the upper face of the main board when ironing pressure is brought to 20 bear upon the sleeve board.

It will be noted that the tapered end of the sleeve board is directed toward the wider or heel end of the main board, so that thereby sleeves of garments may be ironed 15 when stretched over the board 15 in the same position of the operator and by the same hand as that assumed in ironing a skirt. The advantage of this arrangement will be made clear from a consideration 20 of the following: The sleeve of a waist is placed over the sleeve board with its shoulder portion, where it is gathered at its point of attachment to the waist body, at the wider end of the sleeve board, and in 25 ironing the sleeve the operator will stand at the left-hand side of the board adjacent to the heater 25, and by the use of the right hand direct the pointed end of the iron toward the gathered end of the sleeve. The 30 skirt is applied to the main or skirt-board with the gathered or waste-band portion at the narrow part of the board and in position for the operator, standing in the same position as before, and by the use of the 35 right hand, to direct the pointed end of the iron toward the gathered portion of the skirt at the waist-band. In both uses of the board the operator stands in the same position with respect to the iron support 25 40 so that the same movement of the arm both when ironing the sleeve and the skirt carries the iron to said iron support. Thus it becomes unnecessary for the operator to change the iron from one hand to the other 45 when ironing different garments or for the operator to change her position from one side of the board to the other. So far as the general arrangement is concerned, the sleeve board may be optionally arranged to 50 swing either over or under the main or skirt board.

25 designates an iron support which is located in rear and at one side of the main ironing board 10. Said support may 55 constitute also a gas-heated stove by which to maintain the iron heated when not in use. When an electrically heated iron is used the device 25 may constitute merely a support and need play no part in maintaining 60 the iron heated. Said support is maintained on the vertical shaft 18 by means of a laterally directed arm 26 which is sustained on said shaft in any suitable manner. When the support comprises a gas-heated 65 stove, it may be supplied by gas through a

valved supply tube 27 connected to a flexible or other supply pipe 28.

By reason of the fact that the support 25 is located in rear of the ironing board and at the side thereof on which the operator 70 stands, the irons may be readily shifted backwardly off the board without raising the iron and without the necessity of the operator giving special attention in order to place the iron on the board. 75

I claim as my invention:—

1. An ironing board comprising a main or skirt board tapered toward one end, with an iron support at the wider end thereof, a sleeve board disposed in a different vertical 80 plane and tapered toward the wider end of the main or skirt board and the iron support, and supporting means for said sleeve board hinged to a fixed support at the wider end of the skirt board, with means for hinging 85 the forward wider end of the sleeve board to said supporting means.

2. An ironing board comprising a main board, with an iron support at one end thereof, a sleeve board and an arm to one end of 90 which the forward end of the sleeve board is hinged, said arm being hinged at its other end to a fixed support at the rear end of the main board and near said iron support.

3. An ironing board comprising a main board, with an iron support at one end thereof, a sleeve board thereover, a horizontal, swingable L-shaped arm hinged at its shorter end to a fixed support at the rear end of the main board near said iron support and with 100 its longer end extending forwardly along the main board, and a hinge connection between the free end of said arm and the forward end of said sleeve board. 95

4. An ironing board comprising a main board which is tapered toward one end, with an iron support at its wider end, a sleeve board over the main board which is tapered toward the wider end of the main board and a sleeve-board supporting arm hinged to a 110 fixed support near the wider end of the main board and iron support and to which the sleeve board is hinged at the forward wider end of the latter. 105

5. In an ironing board, the combination with a sleeve board, of a supporting arm rigid from end to end thereof, means at one end of said arm to hinge it to a fixed support, and means at the other end of said arm to hinge one end of the sleeve board thereto, 120 said sleeve board extending at its free end toward the hinged end of said arm.

6. In an ironing board, the combination with a sleeve board, of a supporting arm rigid from end to end thereof, and provided 125 at one end with a bearing foot to rest on a horizontal support, means at the other end of said arm to hinge it to a fixed support, and means on said arm above said bearing foot to hinge one end of the sleeve board 130

thereto, with the free end of said board directed toward the hinged end of said arm.

7. The combination with an L-shaped member having means to hinge its shorter arm to a fixed support, of an ironing board lying in a plane over the longer arm of said L-shaped member, and means to hinge the end of said longer arm of the member to the ironing board at the end of said board remote from the shorter arm of said member.

8. In an ironing board, an L-shaped member having means to hinge its shorter arm to a support and provided at the end of its longer arm with a bearing sleeve, and a sleeve board supporting plate hinged at one end to said bearing sleeve and extending at its other end toward the hinged end of said arm.

9. In an ironing board, an L-shaped member having means to hinge its shorter arm to a support and provided at the end of its longer arm with a bearing sleeve, and a sleeve board supporting plate hinged at one end to said bearing and extending at its other end toward the hinged end of said arm, 20 said long arm being provided beneath the hinge of the sleeve supporting plate with a bearing foot.

In testimony whereof, I have hereunto set my hand at Chicago, Illinois, this 8th day 25 of May, 1916.

HERMAN G. GROSSE.
